M. S. GROH

REFRIGERATING MACHINE

Original Filed Feb. 3, 1922

Inventor,
M. S. GROH.

By Fetherstonhaugh & Co.
Atty's.

UNITED STATES PATENT OFFICE.

MELVIN SOLOMON GROH, OF TORONTO, ONTARIO, CANADA, ASSIGNOR TO JOSEPH MERCADANTE, OF NEW YORK, N. Y.

REFRIGERATING MACHINE.

Application filed February 3, 1922, Serial No. 533,905. Renewed June 11, 1924.

To all whom it may concern:

Be it known that I, MELVIN SOLOMON GROH, a subject of the King of Great Britain, of the city of Toronto, in the county of 5 York, in the Province of Ontario, Canada, have invented certain new and useful Improvements in Refrigerating Machines, of which the following is the specification.

My invention relates to improvements in 10 refrigerating machines and the object of the invention is to devise combined pump and condensing chambers for such machines that can be constructed more simply and at less cost than is at present the case. 15 A further object is to so construct the machine that it will be more compact than the present machines wherein the pump and condensing chambers are separate.

My invention consists of a refrigerating 20 machine constructed and arranged all as hereinafter more particularly described and illustrated in the accompanying drawing, in which:

Fig. 1 represents a vertical longitudinal 25 section of a machine constructed according to my invention, and

Fig. 2 is a vertical cross section through the line 2—2 Figure 1.

Like characters of reference indicate corresponding parts in the different views.

1 is the casing provided with the horizontal partition 2 dividing said casing into an upper pump chamber 3 and a lower condensing chamber 4, said casing being open 35 at one end and said open end closed by the cover plate 5 carrying on its inner face a pump 6 adapted to be inserted into the pump chamber 3. The gears of said pump are driven by the spindle 7 extending 40 through a stuffing-box or gland 8 in the face plate and the end of said spindle is suitably connected to the shaft 9 of the motor 10.

11 is a return pipe from the refrigerator 45 coils connected at its upper end to the valve 12 which is in turn connected with the inlet 13 communicating with the pump.

14 is a gas pipe extending in the vicinity 50 of the top of the chamber 3 and the lower end extending in between the double cooling coils 15, which in turn are suitably connected to a source of water supply, said coils being positioned in the lower or condensing chamber 4 is clearly illustrated in the 55 drawing.

16 is a pipe leading from the condensing chamber 4 to the refrigerator coils. 17 is a valve communicating with the condensing chamber 4, the end of the pipe 16 being connected therewith. 18 is an oil supply pipe 60 for the pump extending down from the pump 6 into the oil in the upper chamber 3.

19 and 20 are lower and upper test pet cocks communicating with the upper chamber 3 for testing the level of the oil therein 65 and 21 is a pet cock communicating with the lower chamber 4 for indicating the level of the liquid in the condensing chamber 4.

The operation of the machine is as follows:

The return pipe 11 conveys the gas from the refrigerating coils to the pump 6, said gas being pumped into the chamber 3 by such pump and the pressure in said chamber 3 is built up so that the gas therein is forced 75 through the pipe 14 into the interior of the coils 15 in the condensing chamber 4, such cooling coils condensing the gas and permitting the resultant liquid to drop down into the bottom of the chamber from whence 80 it is led by the pipe 16 back into the refrigerating coils.

The valve 17 is merely a shut off valve for shutting off the liquid from the refrigerator coils and the valve 12 is a shut off valve for 85 the intake to the pump.

Although I have described my machine as constructed with upper and lower chambers formed integrally in one casing it is to be understood that they could with equal facility be so constructed in the casing as to be side by side, the particular relation of one chamber to the other not being of any importance.

It will be apparent that a machine constructed according to my invention will be much more simple and compact than are the machines at present in use and consequently can be constructed much cheaper, having considerably fewer parts.

What I claim as my invention is.

1. In a refrigerating machine, a gas tight casing having a substantially horizontal partition extending across the interior of the same and dividing the casing into pump and condensing chambers, one side of the casing being open, a detachable closure plate having an inwardly extending pump supporting boss formed integrally therewith extending into the pump chamber constituting 105

tuted in the casing, said closure plate closing the open side of the casing and said boss having a refrigerant fluid passage-way and pump drive shaft orifice extending therethrough, and means for establishing communication between the pump and condensing chambers.

2. In a refrigerating machine, a gas tight casing having an open side having a substantially horizontally disposed partition extending toward the open side from the opposite wall, said partition being formed integrally with such wall, a detachable

closure plate having an inwardly extending pump supporting boss formed integrally therewith extending into the pump chamber constituted in the casing, said closure plate closing the open side of the casing and engaging the free edge of the horizontal partition, and said boss having a refrigerant fluid passage-way and a pump drive shaft orifice extending therethrough, and means for establishing communication between the pump and condensing chambers.

MELVIN SOLOMON GROH.
